UNITED STATES PATENT OFFICE.

CHARLES GÉGAUFF, OF MULHOUSE, FRANCE, ASSIGNOR TO SOCIETE ALSACIENNE DE CONSTRUCTIONS MECANIQUES, OF MULHOUSE, FRANCE.

DABBER FOR COMBERS OF THE HEILMANN TYPE.

Application filed September 30, 1926, Serial No. 138,753, and in France October 2, 1925.

This invention relates to improvements in dabbers for combers of the Heilmann type, one object of the invention being to provide improved means for retaining the dabbing blade in the position of rest subsequent to a dabbing movement during an active revolution of the combing cylinder, another object being to provide improved means for actuating the dabbing blade and imparting thereto the required movements for its operation.

With the above and other objects in view, the invention consists in the construction, combination and arrangement of devices hereinafter described and claimed.

In the accompanying drawings

Figure 1 is a diagrammatic sectional view of a comb of the Heilmann type provided with my improved means for retaining the dabbing blade in the position of rest subsequent to a dabbing movement during an active revolution of the combing cylinder.

Figure 2 is a detail sectional view of a comb of the Heilmann type provided with my improved means for operating the dabbing blade.

Figure 3 is a detail diagrammatic front elevation of the same partly in section.

The combing cylinder is indicated at A, its axle shaft *a* being mounted in suitable bearings in a frame *n*. The rows or bars of needles are indicated at *b*, *b'*, *b²* and *b³*. The dabber bar or blade is indicated at D, its front edge being indicated at *d* and its rear edge at *e*. The combing cylinder rotates in the direction indicated by the arrow and the dabber blade, during combing and at the exact instant of passage of the two rows of needles *b'* and *b²* under the end of the upper nipper jaw or member *p* enters suddenly between said bars *b'* and *b²* to energetically dab the lap at this point into the needles. The lap is then held by the nippers.

As in the dabbing operation the bars of the comb have a high circumferential velocity which is that of the comb. It is necessary that the blade *e*, *d*, immediately it falls in to the space between *b'* and *b²* should assume instantaneously the high circumferential velocity of these bars and travel with them through a distance of about two centimeters while moving progressively beyond the effective radius of the points of the needles, there being no need for the dabbing

action to continue for more than a few millimeters of the travel of the bars. Once clear of the comb the dabber moves more slowly and finally stops at the terminal point *d* where it is beyond the path of the needles of the comb. It remains stationary in this position until it again moves into action on the successive evolution of the comb, that is to say, subsequent to the succeeding detaching operation. The detaching operation is generally effected by a pair of fluted rollers *r*, *r'* having an interposed endless leather belt *s* but it may also be effected in any other manner without departure from the present invention. There is shown in Figure 1 the form of the path *d*, *d'*, *d²* traversed in space by the end *d* of the dabber. The inoperative position of the dabber occupied throughout the detaching operation and of the travel of the nippers *p*, *o* between the detaching and the combing positions is shown in dotted lines.

There are two systems of circular combing in combs of the Heilmann type according to the material worked, wool, flock silk, cotton, etc. The first system is that which has been described above and which is the most usual. The circular comb makes only one revolution per evolution of the machine. In the other system the comb makes two or three revolutions per evolution of the machine while turning continuously, but one only of these revolutions is employed for the combing operation while the two others are only inoperative revolutions, that is to say, without combing. This device has for its object to obtain a much higher circumferential speed of the comb and in consequence to be able, during the short interval when the nippers present the lap or the like to the comb, to cause the latter to traverse it for a greater arc of the circumference of the comb, that is, to give a larger number of strokes of the bar to increase the degree of straightening of the combed material.

In this second system it is necessary to employ means to prevent the dabber from working, that is, from travelling over the path *d*, *d'* during the inoperative revolutions which the comb makes because there would be produced rapid and useless wear of the mechanism of the dabber, which is only required to operate during the rotation of the comb employed for combing the lap. In order to put the dabber out of operation

during these inoperative revolutions the lower jaw o of the nippers is in accordance with my invention provided on each side with a finger t . The latter, when the nippers occupy the position during detachment indicated in dotted lines o', t' in Figure 1, occupies the position t' , thus closing the path for the dabber D . The latter is thus held detained during the free revolutions of the comb which the latter makes during the combing period.

Other suitable means may within the scope of my invention be provided for thus detaining the dabber blade.

I will now describe my improved means for operating the dabber bar and which improved means is illustrated in detail in Figures 2 and 3 of the drawing. The dabber blade D is carried by a pair of rocking arms F and is secured pivotally at each end as at f to the upper end of one of said arms. The pivots f pass through depending lugs f' with which the dabber blade is provided, each of said lugs having an arm f^2 . Each arm F has a stop lug h to bear under the free, dabbing portion of the dabber blade to limit its movement toward the center of the combing cylinder as shown in Figure 2, springs J being provided to move the dabber bar in such direction, each of said springs being connected at one end as at i to the arm f^2 and at the other end to the arm F as at j .

The arms F have fixed pivots h at a point spaced from their inner ends and on which they rock, said pivots being secured to the frame n . Each of the said arms is also provided at a point spaced from its pivot h with a tappet roller G which is mounted for rotation on a stud g with which the arm is provided. Springs u are connected to the inner ends of the arm f to move the latter in a direction substantially reverse to that of the rotation of the combing cylinder and in connection with the means hereinafter described impart dabbing movement to said dabber blade.

The combing cylinder is provided on each side of the bars of needles with a sector c , the periphery of which is indicated at c' and each sector has a peripheral notch c^2 arranged between the bars b', b^2 and of appropriate shape and depth to receive the free edge d of the dabber and permit dabbing movement thereof.

The shaft a of the combing cylinder is provided at points near the ends of said cylinder with cams M . Each cam is of the shape shown in Figure 2, provided with a semi-circular portion which provides a peripheral surface m^3, m^4 concentric with the shaft. Each cam also has a reentrant portion m^2 which extends from the point m^3 and merges into a substantially quarter-circular portion m' which connects said reen-

trant portion with the concentric peripheral portion of the cam. The springs u are active to turn the arms F on their pivot h to impart dabbing stroke to said arms and the dabber blade carried thereby and keep the roller g always in contact with the peripheries of the cams. During such dabbing movement and while the dabber is approaching the notches c^2 , the pivot f of the dabber moves in an arc of a circle indicated by the dotted line d^1, d^2, d^3 in Figure 2 which are at the point d' intersects the arc represented by the periphery of the sector c , owing to the eccentricity of the pivot axis h of the arms F with respect to the axis of rotation a of the combing cylinder. Such movement of the arms F is permitted by the cam surfaces m', m^2 as will be understood. When the free edge d of the dabber blade reaches the notches c^2 it is forced into such notches, between the bars of needles b', b^2 by the action of the springs j .

The free end or edge d of the dabber will not be liable in the course of its travel to contact with the points of the needles of the comb because it will be pressed on each side of the comb against the sectors c, c^2 which maintain it raised, that is, the end d will no longer rest on its usual seating k but on the outer periphery of the two sectors c of the comb. Figure 2 thus represents at about one-third of the travel the position d' of the end of the dabber and also at d^2 the final position of the travel, the fall of the end d^2 having just taken place.

When the recess c^2 has been thus engaged by the end d^2 of the dabber the latter will participate in the movement of the cylinder and sectors and the part m^2, m^3 of the eccentric will actuate only momentarily the arms F through their rollers g and will only again take action after the dabber d^2 entrained by the recess c^2 shall have moved over a certain distance (about 15 millimeters). From this moment the part m^2, m^3 of the eccentric will actuate the dabber and take it to its final position of rest at e, d , represented in full lines in Figure 2 and during this period the seating k of the dabber will support the end d of the dabber and maintain it clear of the points of the needles. The dabber will thus remain as already explained above in this position of rest until it again moves into action, that is to say, until the succeeding combing period.

My improved means for operating the dabber is much simpler in construction and provides for a much higher speed than that heretofore in use and is effective with precision to perform the dabbing operation.

Having thus described my invention, I claim:

1. In dabbing mechanism, in combination with a combing cylinder, a dabbing blade, and nipper elements, means on one of said

nipper elements to retain the said blade in the position of rest, subsequent to a dabbing movement, during an active revolution of the said cylinder and during the succeeding 5 inactive revolution of said cylinder.

2. In dabbing mechanism, a combing cylinder having a needle bar sector provided with a peripheral notch, a rocking arm having a pivotal axis eccentric to the axis of 10 rotation of the cylinder, a dabber blade carried by said arm in an arc which intersects the arc represented by the periphery of the sector, and mounted for pivotal movement with respect to said arm, means to actuate 15 said rocking arm and means to engage said dabber blade with said notch.

3. In dabbing mechanism, a combing cylinder having a needle bar sector provided with a peripheral notch, a rocking arm having a pivotal axis eccentric to the axis of 20 rotation of the cylinder, a spring active to move said arm in one direction to impart dabbing movement thereto, and a cam active to momentarily hold said arm in initial position and to permit such movement of such 25 arm by said spring, a dabber blade carried by and pivotally mounted on said arm and a spring active to cause said blade to engage its free end into such notch of said sector when such notch is reached thereby. 30

In witness whereof I affix my signature.

CHARLES GÉGAUFF.
